UNITED STATES PATENT OFFICE.

MAILLER SEARLES, OF OAKLAND, CALIFORNIA; CLARA CLIFT SEARLES, EXECUTRIX OF SAID MAILLER SEARLES, DECEASED, ASSIGNOR TO MAILLER SEARLES, INC., OF SAN FRANCISCO, CALIFORNIA, A CORPORATION OF CALIFORNIA.

ENDLESS ELEVATOR.

Application filed December 11, 1922. Serial No. 606,287.

To all whom it may concern:

Be it known that I, MAILLER SEARLES, a citizen of the United States, residing at Oakland, in the county of Alameda, State of California, have invented a new and useful Endless Elevator, of which the following is a specification in such full and clear terms as will enable those skilled in the art to construct and use the same.

10 This invention relates to an endless elevator especially adapted to the piling of sacks and boxes in high piles, and one of the objects of the invention is to provide means whereby the boxes or sacks handled thereby will be properly delivered from the elevator at the top of the same.

It will be understood by those skilled in the art that in the operation of piling machines of his character, it is necessary to provide a discharge roller at the upper end of the elevator run, separate from the elevator itself. This roller must be at a certain fixed distance from the elevator run itself regardless of the fact that the elevator run must be adjusted, from time to time, due to slackness of the chains making up the elevator. The result of this is that the discharge roller must be carried at a fixed distance from the roller at the top of the elevator run regardless of its adjustment, and this object is attained in the present invention, by carrying the discharge roll along with the adjusting means.

Another object of the present invention is to provide means whereby the elevator run may be raised or lowered by power without danger of seriously injuring any part of the apparatus, if the workmen neglect to supply it at the precise moment that it should be supplied, or if it is not cut off when it should be.

Another object of the invention is to provide means whereby the shaft transmitting power to the elevator lifting apparatus will make use of but one thrust bearing for either lifting or lowering the elevator run.

Another object of the invention is to provide means whereby the elevator run will be held at any given elevation by the gears operating it unless the workmen positively operates the gearing to raise or lower it.

Other objects of the invention will appear as the description proceeds.

An embodiment of the invention is shown in the accompanying drawings in which the

same reference numeral is applied to the same portion throughout, but I am aware that there may be modifications thereof.

Fig. 1 is a longitudinal sectional view of the complete apparatus,

Fig. 2 is a side elevation of the top of the elevator frame showing the package discharge roller,

Fig. 3 is a plan view of the elevator with a portion of the endless chain run broken away for the purposes of illustration.

Fig. 4 is a plan view of the roller at the top of the elevator run, and

Fig. 5 is a side elevation of the friction bevel gears used for raising and lowering the elevator.

The apparatus comprises a rectangular truck having two longitudinally extending stringers. These stringers are connected together by means of suitable cross-bars 3 to 6 inclusive. Gusset plates 7 to 10 inclusive are connected to the side members and cross members 3 and 6 at their corners to stiffen the frame, and to form suitable bearings for the castor wheels 11 to 14 inclusive. The ends of the side members 1 and 2 overhang the rear castor wheels and are connected to the endless elevator frame by means of two bearings 15 and 16, said bearings being applied on the lower end of the angle frame built up of the side members 17 and 18. The pair of members are connected together by suitable diagonal bracing 19 and other suitable rectangular bracing, as indicated at 20.

At the forward end of the frame there are two posts 21, 22 connected to suitable braces 23, 24, and connected together by means of the cross-bar 25.

On the front end of the frame and secured to the cross-bar 6 are two brackets 27, 28 to which the elevator bars 29, 30 are connected.

At their upper ends the lifting bars are connected together by a shaft 31, which shaft has rollers 32, 33 at its ends. The shaft 31 is also connected to two eye-bolts 34 which eye-bolts are connected to two turn buckles 35 in turn connected to two eye bolts 36. The eye-bolts are connected to the shackle of a single pulley 37, in each side of the frame.

A cable 38, on each side of the truck frame, has one end secured thereto, as indicated at

39 and the other end of the cable passes around a drum 40, another drum 41 being also provided at the other side of the machine for the other cable 38.

5 The drums 40, 41 are mounted rigidly upon a shaft 42 and said shaft also has a pair of bearings 43, and 44 around the same adjacent the worm wheel 45.

10 The two bearings 43, 44 are connected together by a plate 46 and which plate is connected to the underside of the cross-bar 3. This plate also carries two bearings 46, 47 for a short shaft 48, and it has a worm 49 in mesh with the worm-wheel 45. This 15 shaft also has a universal joint 50 to connect it with another shaft 51, on the end of which is a bevel friction wheel 52.

20 The shaft 51 passes through a bearing 53 pivotally mounted on the underside of the cross-bar 4. At about the middle of the frame there is a shaft 54 suitably journaled in said frame and said shaft carries the drive pulley 55, two bevel pulleys 56, 57, a sprocket gear 58 and clutch 59.

25 The clutch 59 is operated by a bell-crank lever 60 connected to a rod 61, which rod is in turn connected to the operating handle 62, the latter pivotally mounted on the side member 1.

30 It will be seen that the two bevel wheels 56, 57 are as close to the wheel 52 as it is possible to place them and still permit them to ride free normally.

35 Between the shaft 42 and the shaft 54 there is another shaft 63. This shaft has the sprocket wheel 64 thereon and a sprocket wheel 65. The latter sprocket wheel has a chain 66 extending therefrom to the endless elevator drive sprocket 67 on the shaft 68, 40 said shaft also extending through the bearings 15, 16 but carrying no other load than the load necessary to operate the endless chains 69, 70.

45 An endless sprocket chain 58' extends from the sprocket wheel 58 to the sprocket wheel 64 and drives the latter.

50 At the front of the machine there are two longitudinally extending sills 80, 81 upon which the motor 82 is supported, a belt 83 extends from the motor pulley to the pulley 55 to drive the machine.

55 The bearing 53 is pivotally mounted on a bearing 53' secured on the underside of the channel-bar 4. A rod 85 connects the lower portion of said bearing with an arm 86 on a short vertical shaft 87, said shaft being mounted in a bearing 88 on the inside of the longitudinally extending frame member 2. On its upper end the shaft 87 60 has a long lever 89 rigidly connected therewith. This lever extends across the frame and terminates over the longitudinally extending frame member 1. Connected with this lever is a rod 90 with a hand grip portion 91, at its end adjacent the handle 62,

The length of the lever 89 is so considerable that it gives the workmen sufficient leverage to push the bevel friction wheel 52 into engagement with either the wheel 56 or 57 to raise or lower the elevator carrying frame, and since the torque on the shaft 42, due to the weight of the apparatus is resisted by the worm wheel and worm 49, and regardless of whether the workmen happens to hold the wheel 52 in engagement with the wheels 56, 57 too long, he cannot injure the apparatus because when the apparatus reaches the end of its allowed movement, the frictions will slip.

70 The side frames 17 of the elevator are connected by any suitable floor 100 which terminates adjacent the upper sprocket shaft 101. This sprocket shaft carries two sprocket wheels 102, 103 and the shaft is journaled in two bearings 104, 105 which 75 bearings are in turn flexibly supported by two fixtures 106, 107, each with depending lugs 108, 109.

80 An adjusting screw 110 passes through each of the depending lugs 108, 109 and has 80 a lug 111 at its upper end passing through a hole in a short angle-bar 112, which connects the upper member 17 with the lower member 18 at their upper ends.

85 Immediately at the rear of the screw 110 95 there is a short angle-bar 113 connecting the upper and lower member 17, 18, and the two angle members 112, 113 are slotted to receive a bar 114, said bar being also connected to the lug 108 so that said bar moves 100 along with the member 106.

90 At its upper end bar 114 is bent upwardly as shown in 115, and the roller 116 is journaled thereon. On the opposite side of the frame a bar 114' supports the other end of 105 the roller 116, and is connected to the bearing support 107 in the same way as the bar shown in Fig. 2.

95 On the side of the member 17 between the two angle bars 112, 113 there is secured an 110 angle bar 120. This bar is slotted to allow the set-bolt 121 to move as the bearing fixture 106 moves when the slack of the chains 69, 70 is taken up.

115 In order to provide means for pulling objects, such as sacks or boxes up the inclined plane, the chains 69, 70 are connected by means of a plurality of bars 122, said bars having wheels 123, 124 at their ends which ride upon the top of the upper angle bars 17. 120

125 What I claim is as follows, but various modifications may be made in the construction shown in the drawings and above particularly described form, within the purview of my invention:

1. An elevating machine comprising an inclined support, endless chains passing over said support, flights connecting said chains to carry packages up the incline, adjustable sprocket wheels at the top of the incline 130

over which the chains pass, a discharge roller for the packages and a pair of slideable bars to support said discharge roller at a fixed distance from the sprocket wheels at the top of the incline in all adjustments thereof, said support being movable with the adjustment of the sprocket wheels and each bar having a double support in the inclined frame.

2. In an elevating machine the combination with an inclined support of a pair of sprocket chains passing thereover, flights connecting said sprocket chains to carry packages up the incline, sprocket wheels at

the top of the incline over which the chains pass, a discharge roller over which the packages pass when leaving the chains, means to adjust the chain sprockets at the top of the incline and slideable arms connected with said adjusting mechanism for supporting the discharge roller at a fixed distance from the chain sprockets at all positions of the adjustment of said chain sprockets said arms being slideable with the sprocket wheels.

In testimony whereof I have hereunto set my hand this 20th day of November A. D. 1922.

MAILLER SEARLES.
